Primary Examiner — Cynthia M Chin(74) *Attorney, Agent, or Firm* — Knobbe, Martens, Olson & Bear, LLP(57) **CLAIM**

The ornamental design for a scooter connector tubing, as shown and described.

DESCRIPTION

FIG. 1 is a perspective view of a scooter connector tubing. FIG. 2 is a front elevational view of the scooter connector tubing of FIG. 1.

FIG. 3 is a rear elevational view of the scooter connector tubing of FIG. 1.

FIG. 4 is a left side elevational view of the scooter connector tubing of FIG. 1.

FIG. 5 is a top plan view of the scooter connector tubing of FIG. 1; and,

FIG. 6 is a bottom plan view of the scooter connector tubing of FIG. 1.

The broken lines in the drawings are for illustrative purposes only and form no part of the claimed design.
